CLAIM

The ornamental design for a strap-on dildo, as shown and described.

DESCRIPTION

FIG. 1 is a top plan view of a strap-on dildo, showing my new design;

FIG. 2 is a bottom plan view thereof;

FIG. 3 is a left side elevation view, the right side elevation view being a mirror image thereof; and,

FIG. 4 is a bottom view thereof.

1 Claim, 4 Drawing Sheets

FIG. 1

FIG. 2

FIG. 3

FIG. 4
